UNITED STATES PATENT OFFICE

132,289

DESIGN FOR A CLEANING GUN UNIT

Max C. Thompson, South Pasadena, Calif.

Application October 3, 1941, Serial No. 103,618

Term of patent 14 years

To all whom it may concern:

Be it known that I, Max C. Thompson, a citizen of the United States, residing at South Pasadena, in the county of Los Angeles and State of California, have invented a new, original, and ornamental Design for a Cleaning Gun Unit, of which the following is a specification, reference being had to the accompanying drawing, forming part thereof.

Figure 1 is a top plan view of a cleaning gun unit showing my new design;

Figure 2 is a side elevational view thereof; and Figure 3 is a rear end elevational view thereof.

I claim:

The ornamental design for a cleaning gun unit, as shown.

MAX C. THOMPSON.
